Patented Aug. 17, 1920.

UNITED STATES PATENT OFFICE.

ARTHUR J. FILKINS, OF CHICAGO, ILLINOIS.

SMOKEJACK.

1,349,666.

Specification of Letters Patent. Patented Aug. 17, 1920.

Application filed March 7, 1919. Serial No. 281,120.

To all whom it may concern:

Be it known that I, ARTHUR J. FILKINS, a citizen of the United States, residing at Chicago, in the county of Cook and State 5 of Illinois, have invented certain new and useful Improvements in Smokejacks, of which the following is a specification.

The invention relates to new and useful improvements in chimneys of the type more 10 commonly called smoke-jacks, used for conducting the exhaust smoke and gases from locomotives while in round houses, running sheds, or in the train sheds of depots or terminal buildings.

15 It is one of the primary objects of the invention to provide an automatically or draft operated cover for the upper and outer end of the exhaust pipe or stack of a chimney or smoke-jack of the described 20 character.

It is a further object of the invention to provide improvements in the construction of the roof collar used for supporting a smoke-jack of the described character.

25 It is a further object of the invention to provide certain improvements in the structure of the hood or smoke collector as usually provided at the lower end of the smoke-jack by which the same may be 30 formed in part of overlapped gray iron or cast iron plates, the construction of the hood being such that in parts of the hood, as the vertical sides, light and inexpensive substitutes for gray or cast iron may be employed, such as chemically treated fireproof 35 wood and the whole secured together and suspended in a substantial manner from the roof collar, by which the entire device is supported in relation to the roof or top 40 of the building upon which the device is installed.

Other objects of the invention will appear from the following description which is directed to the preferred embodiment of 45 the invention shown in the drawings forming a part of this specification, and finally pointed out more particularly in the appended claims.

In the said drawings, Figure 1 is a side 50 elevational view of the complete device as installed upon the roof of a round house, the support for the device upon the roof of a round house being shown also in section.

Fig. 2 is a view similar to Fig. 1, being 55 taken at right angles to the view of Fig. 1 and showing an end elevation of the device

with the roof supporting means in section as in Fig. 1.

Fig. 3 is a top plan view of the roof collar plate, and Fig. 4 is an enlarged detail 60 sectional view taken on line 4—4 Fig. 3.

The reference character 10 indicates generally the roof or top covering of the round house or other building on which the smoke jack embodying the invention is supported 65 in any desired or usual manner as upon the roof timbers 11. 12 is an extension formed on the roof of any suitable material, being adapted to furnish a direct support or foundation upon which may be carried the 70 collar plate designated by the reference character 15, for supporting the smoke-jack.

It is found that in the use especially of 75 certain forms of bituminous coal, as used in firing locomotives, that there is an injurious amount of acid suspended in the exhaust gases. Gray or cast iron is one of the best known cheap metals for withstanding the corrosive effect of such acids, and 80 consequently I prefer to construct the metallic parts of my smoke-jack or chimney of gray or cast iron, particularly where there is any liability of the parts of the device becoming exposed to the acid action 85 of the exhaust escaping by way of the device. Consequently, I prefer to construct the main pipe portions 16 and 17 above the roof collar 15, of gray iron, one of the pipe sections being bell-mouthed or enlarged at 90 one end as indicated at 17^a to coöperate with the adjacent section of the pipe, the pipe sections being locked together by suitable pierced lugs through which are passed the retaining bolts 18. The lower section 95 16 may be slightly bell-mouthed or enlarged as at 16^a to coöperate with the upwardly extending annular rib 15^a around the opening 19 in the collar plate 15.

Below the collar plate 15 the smoke pipe 100 or stack is extended downwardly by short section 20 formed with radial lugs 21 preferably on diametrically opposite sides which are pierced and take the retaining bolts 22 for securing the pipe section 20 to the roof collar plate. As stated the pipe sections 17 and 16, the collar plate 15, and the short section 20 are preferably formed of gray or cast iron, and to the lower extremity of the pipe section 20 there is secured an extended 110 or downwardly extending section 23, also preferably formed of gray iron and an-

chored to the pipe section 21 by telescoping joint 20^a, similar to the joint 17^a, the parts being locked together by one or more retaining bolts 24 passing through the pierced registering lugs on the respective sections. It will be seen that the section 23 is enlarged or expanded downwardly on only one diameter so as to elongate the bell-shaped hood as indicated in Fig. 1, but not 5 to substantially increase its width, as will be apparent from end elevational view, Fig. 2. The diverging ends of the hood are preferably formed of two or more gray iron plates 24, 25, which may be secured together by suitable retaining means as by rivets or bolts indicated by reference character 26. I prefer to form the substantially vertical sides of the hood below the section 23 of tongue and grooved wood strips, which are preferably 10 treated to render same as nearly fire proof as possible. The end sections 24, 25 of the hood may be formed with the right angular lateral edges as indicated at 24^a and 25^a and pierced to take suitable retaining means as 15 screws or bolts for securing the wood strips thereto, said strips being designated by the reference character 30. On one of the series of plates 24 or 25, there are formed lugs 25^b which are pierced and in which are secured the ends of lateral stay rods or tie rods 31 for anchoring the series of end plates 24, 25 together, and preventing any 20 tendency of the metallic ends of the hood to warp or spread apart from the wood sides. 25 Obviously, when the sides of the hood are constructed of wood, the weight of the hood to be supported from the roof collar 15, will be much less than where the entire hood is made of gray or cast iron. Ordinarily, it is 30 necessary to provide a hood several feet in length to allow some latitude in positioning a locomotive stack thereunder and obviously the elongated diameter of the hood will extend in the direction of travel of the locomotive since the position of the track below 35 will determine the position of the hood laterally. This will result in a hood of considerable weight in view of its necessarily extended length, and in order to further secure and safely suspend the hood from the 40 collar plate 15, I provide a plurality of openings in the collar plate 15 as indicated at 15^b through which are passed the stay rods 33, the lower ends of which are secured 45 to lugs on anchor plates 34, the latter being secured in any desired manner to the side strips 30 of the hood. It is preferred that the upper ends of the rods be screwthreaded and provided with adjusting nuts on the 50 upper side of the collar plate 15.

The construction of the collar plate 15 is of importance in order to properly perform its functions in supporting the smoke-jack properly upon the roof of the building or 55 on the special collar or extension 12, pro-

vided for coöperating with same. The plate 15 is accordingly provided with a downwardly projecting peripheral flange 15^c affording a cover or joint over the roof collar 12, and in coöperation with the upwardly extending pipe flange 15^a, insuring that any water due to condensation or the elements, will be shed from the top thereof upon the building.

Another important feature of my invention resides in the special construction of the collar plate 15 by which destructive fumes not entirely cared for upon the inside of the hood of the smoke-jack, and which have a tendency to accumulate below the collar plate 15, and between the roof collar 12 and the pipe section 20, are vented from the opening between the pipe and the roof below the collar plate to the outside atmosphere. This result is obtained by the provision of a plurality of curved slots 15^d which are completely surrounded by raised edges 15^e, designed to prevent the passage downwardly through slots 15^d of any water from the upper and outside of the collar 90 plate 15.

I will now describe my automatic damper, or pipe controlling device. Near the top of the upper pipe section 17 is mounted a rigid upright 40 to the upper end of which is pivoted at 41, an extended arm 42, one extremity of which carries a cover 43 adapted to close the upper end of the pipe. The arm 42 is adapted to have a swinging movement so as to lift the cover 43 to clear the upper end of the pipe to permit of a normal draft of air and gas therethrough when desired, and the lever 42 including the adjustable cover 43 carried thereby, is controlled or counterbalanced by weight 44 on the free end thereof beyond the pivot 41, and this weight 44 is made adjustable by suitable means as the set screw 45. By moving the weight 44 as may be necessary along the arm 42 and securing it in its adjusted position the damper or cover 43 may be adjusted to normally close the top of the pipe and yet be so nearly counterbalanced by the weight 44 that any pronounced upward draft of hot air, gases or smoke passing through the pipe will cause the counterweight to raise the cover or damper to the open position as long as there are gases to be discharged from the interior of the building. The importance of this automatically operating damper or cover for the smoke-jack will be apparent, since it will be seen that upon the cessation of an outgoing discharge the cover will overbalance the weighted arm and the pipe will automatically be closed and a down draft prevented. Down drafts are to be avoided because they carry cold air not desired into a roundhouse in such quantities as to make the heating of the interior impractical or impossible. It has been the 130

practice heretofore to require hand operated dampers to be installed on all new smoke-jacks. In practice employees forget to close them upon the removal of an engine from a given stall, or the damper operating device sometimes becomes misplaced or inoperative with the result that the smoke-jack passage-way is commonly left open. The hand operating cable 46 may be provided to operate the cover when there is no forced outer draft, or when the device is out of adjustment.

In the use of my improved structure it will be seen that the chimney of the device is normally kept closed, and will be opened automatically without any attention from an operator.

At 48, 49 I show troughs adapted to collect any water of condensation from the inside walls of the smoke-jack, and to discharge same through suitable ducts 50 to prevent deposits of same upon an engine being vented beneath the device.

I claim:

25 1. In a smoke-jack or chimney for round houses and the like, the combination with a vent pipe adapted to extend through the roof of the building and being designed to form substantially a continuation of the 30 smoke pipe or stack of a locomotive and leading from the interior of the building to the exterior thereof, of means for collecting and conveying the exhaust of a locomotive to the lower extremity of the pipe on the 35 interior of the building, an integral cover for the outer and discharge end of the said pipe, and a counterbalance device by which said cover is supported in position to normally close the outer or discharge end of 40 the pipe.

2. In a smoke-jack or chimney for round houses and the like, the combination with a vent pipe adapted to extend through the roof of the building from the interior to the 45 exterior thereof, of means for collecting and conveying the exhaust of a locomotive to the lower extremity of the pipe on the exterior of the building, a cover for the outer and discharge end of the said pipe, and a counterbalance device by which said cover is supported in position to normally close the outer or discharge end of the pipe, the said counterbalance device being so adjusted that the friction or pressure of heated gases being discharged upwardly through the vent pipe will cause the counterbalance device to elevate the cover to open the discharge end of the pipe but will permit the normal closing of the same upon the cessation of the discharge of said gases through the pipe.

3. In a smoke-jack or chimney for round houses and the like, the combination with a pipe adapted to extend through the roof of the building from the interior to the 65 exterior thereof, of means for collecting and

conveying the exhaust of a locomotive to the lower extremity of the pipe on the interior of the building, a cover for the outer and discharge end of said pipe, means for operably connecting the said cover to open and close the outer and discharge end of the said pipe, and a counterbalance device related to said cover operating means whereby the cover will normally close the outer and discharge end of the pipe but will open upon the passage of heated air or gases upwardly through the pipe.

4. In a smoke-jack or chimney for round houses and the like, the combination with a pipe adapted to extend through the roof of the building from the interior to the exterior thereof, a movable cover for the outer and discharge end of the said pipe and means for adjustably securing the said cover in relation to the pipe comprising a counterbalance device adapted to support the cover normally in position to close the upper discharge end of the pipe, but being adapted to be lifted above the top of the pipe by the combined lifting effect of the pressure of heated air or gases passing upwardly through the pipe when added to the lifting effect of the counterbalance device.

5. In a smoke-jack or chimney for round houses and the like, the combination with a pipe adapted to extend through the roof of the building from the interior to the exterior thereof, of means for collecting and conveying the exhaust of a locomotive to the lower extremity of the pipe on the interior of the building, a cover for the outer and discharge end of the pipe, the said cover being detachably connected in relation to the pipe and a counterbalance device connected with the cover, the said counterbalance device being capable of adjustment whereby the normal weight of the cover and associated parts will cause the cover to normally close the upper end of the pipe but to be lifted by a rising current of heated air or gases passing through the said pipe.

6. In a smoke-jack or chimney for round houses and the like, the combination with a vent pipe adapted to extend through the roof of the building from the interior of the building to the exterior thereof, of means for collecting and conveying the exhaust of a locomotive to the lower extremity of the pipe on the interior of the building, a cover for the outer and discharge end of the said pipe, a standard on the exterior of the pipe adjacent the discharge end thereof, a lever arm pivotally connected with the standard and operatively connected with the cover, and a counterbalance weight secured to the said lever.

7. In a smoke-jack or chimney for round houses and the like, the combination with

a vent pipe adapted to extend through the roof of the building from the interior of the building to the exterior thereof, of means for collecting and conveying the exhaust of a locomotive to the lower extremity of the pipe on the interior of the building, a cover for the outer and discharge end of the said pipe, a standard on the pipe adjacent the discharge end thereof, a lever arm 10 pivotally connected with the standard and operatively connected with the cover, and an adjustable counterbalance weight secured to the said lever.

8. In a smoke-jack or chimney for round houses and the like, the combination with a vent pipe adapted to extend through the roof of the building from the interior of the building to the exterior thereof, of means for collecting and conveying the exhaust of a locomotive to the lower extremity of the pipe on the interior of the building, a cover for the outer and discharge end of the said pipe, a standard on the pipe adjacent the discharge end thereof, a lever arm 20 pivotally connected with the standard and operatively connected with the cover, an adjustable counterbalance weight secured to said lever, and a flexible connection extending from said lever through the roof 25 of the building to which the smoke-jack or chimney is attached to the interior of the adjacent exhaust collecting means.

9. In a smoke-jack or chimney for round houses and the like, the combination with a vent pipe adapted to extend through the roof of the building from the interior to the exterior thereof, of means for collecting and conveying the exhaust of a locomotive to the lower extremity of the pipe on the interior of the building, there being an opening in the roof of the building larger than the normal diameter of the pipe for the passage of the said pipe therethrough, a collar plate for supporting the pipe being rigidly secured thereto and being extended peripherally from the pipe to contact with supporting means carried by the roof of the building adjacent the said opening therein, with the upper surface of said collar plate 45 exposed to atmosphere around the outer periphery of said pipe, there being one or more openings in the said collar plate providing communication between the interior and exterior of the building on the exterior 50 of the pipe, and means for preventing the downward passage of water through the said plate comprising upwardly projecting continuous ribs surrounding the said openings in said plate.

10. In a smoke-jack or chimney for round houses and the like, the combination with a vent pipe adapted to extend through the roof of the building from the interior to the exterior thereof, of means for collecting and

conveying the exhaust of a locomotive to 65 the lower extremity of the pipe on the interior of the building, and a collar plate secured to the pipe to support the weight thereof in relation to the building roof, there being a downwardly projecting outer peripheral flange on the cover plate and a plurality of openings through the said plate, each of said openings being surrounded by continuous upwardly projecting ribs adapted to prevent the passage of liquids accumulating 75 upon the upper side of the plate through the said openings therein to the interior of the building.

11. In a smoke-jack or chimney for round houses and the like, the combination with a 80 pipe adapted to extend through the roof of the building from the interior to the exterior thereof, a collar plate secured to the pipe, and means for collecting and conveying the exhaust of a locomotive to the lower 85 extremity of the pipe on the interior of the building comprising a metallic section secured to the lower end of the pipe and having two of its opposite sides diverging downwardly, a plurality of metallic extension 90 plates secured to the downwardly diverging walls of the metallic pipe section, the side edges of the said plates being connected by comparatively weak or fragile strips of suitable fire-proof material, stay rods connecting the downwardly diverging plates of the hood near the lower extremity of each series thereof and tending to hold said extension plates in their normal positions in relation to the ends of said strips of fire 100 proof material, and a plurality of supporting rods secured to the side walls of the hood and extending thence to the said collar plate 95 whereby to support the side walls of the hood from the collar plate.

12. In a smoke-jack or chimney for round houses and the like, the combination with a vent pipe adapted to extend from the interior of the building to the exterior thereof, said pipe being supported upon the roof of 110 the building by suitable means connecting same with said roof, a metallic extension of the pipe section supported by and below the collar plate and having two of its sides diverging downwardly, a composite gas and 115 smoke collecting device or hood forming a continuation of said metallic extension of the pipe and comprising a plurality of end and side pieces or plates secured together, and a plurality of supporting rods each attached at its extremities to the opposite end plates of the hood to prevent the separation 120 of said end plates from the side plates of the hood.

In testimony whereof I have signed my 125 name to this specification on this 26th day of February, A. D. 1919.

ARTHUR J. FILKINS.
